DISPLAY CARTON

Wilbur C. Wallbank, Chicago, Ill., assignor to
 Chicago Carton Company, Chicago, Ill., a corporation of Illinois

Application July 21, 1932, Serial No. 623,801

3 Claims. (Cl. 206—44)

This invention relates to display cartons for articles of merchandise, and has reference more particularly to a type of such cartons usually made of cardboard or similar material which may be readily manipulated so as to either fully enclose and protect the articles or display the articles in an attractive manner.

One object of the present invention is to provide a carton of the character above indicated which may be economically manufactured from comparatively light or thin cardboard or the like and yet shall possess ample strength and rigidity to serve the purposes of both a packing and shipping container and a display receptacle. Another object is to provide a carton which when closed may have the form of a plain rectangular box, and when open may present a stepped form adapted to display the goods on a plurality of levels, thus increasing the display capacity. Another object has been to provide a carton of this type having a hinged and foldable member that in one position serves as a cover or closure for the carton and in another position serves as a display tray. Another object has been to provide, in a carton having a hinged cover openable to display the goods, a construction affording to the side and end walls of the body and cover smooth, rounded and reinforced free edges that will not become torn or frayed in handling and will present a neatly finished appearance; and a further object has been to provide a carton well adapted for the prominent display of advertising matter on both the inner and outer surfaces of its walls.

Further objects and advantages will appear from the following description of a selected form of the invention, which is illustrated in the accompanying drawings wherein—

Fig. 1 is a perspective view of the carton in closed position.

Fig. 2 is a perspective view of the same in open or display position.

Fig. 3 is a longitudinal vertical median section of the box in closed position.

Fig. 4 is a plan view of the blank.

My improved display carton may be, and preferably is, formed from a single suitably cut and scored blank of paper-board or light cardboard, although to a greater or less extent the parts may be united by paste or otherwise instead of being formed from a single sheet or blank.

First describing this blank, in the plan view thereof, Fig. 4, the solid lines represent cuts in the blank and the dotted lines represent lines of bend or fold. The longitudinal central portion

of the blank comprises, from left to right, a front end wall flap 10, a front end wall 11 of the body, a bottom wall 12 of the body, a rear end wall 13 of the body, a top wall 14 of the body, a top wall 15 of the cover, an end wall 16 of the cover, and an end wall flap 17; these parts being marked off from each other by the fold lines *a*, *b*, *c*, *d*, *e*, *f* and *g*. Continuous with each longitudinal edge of the bottom wall 12 is a side wall 18 of the body marked off from the bottom wall by a fold line *h*, and continuous with the outer or upper edge of each side wall 18 is a side wall flap 19 marked off from the side wall 18 by an oblique fold line *i* and a side wall flange 20 marked off from the side wall 18 by a longitudinal fold line *k*. Continuous with the rear ends of the side walls 18 of the body, and marked off therefrom by the fold lines *l* are outer and inner flaps 21 and 21' that, when the carton is set up, are folded inwardly over each other and over the rear end wall 13 of the body, as hereinafter more fully described.

On opposite edges of the top wall 14 of the body are locking tongues 22 that, in the assembled position of the carton, enter slots 23 in the side wall flanges 20; and continuous with the top wall 15 of the cover and marked off therefrom by fold lines *m* are cover side walls 24. Continuous with the outer or upper edges of the cover side walls 24, and marked off therefrom by oblique fold lines *n* are side wall flaps 25 that, in the assembled form of the carton are folded down against the inner sides of the cover side walls 24, and are provided on their free edges with locking tongues 26 that enter slots 27 in the cover top wall 15. Continuous with the narrow end of each cover side wall 24, and marked off therefrom by a fold line *o* is a wing 28 that is separated from the top wall of the body by a cut *p*; and continuous with the wide end of each cover side wall 24 and marked off therefrom by a fold line *q* is a side wall wing 29 that is folded inwardly between the cover end wall 16 and the end wall flap 17 when the box is assembled. The free end edge of the end wall flap 17 carries locking tongues 30 that enter slots 31 in the cover top wall 15.

The outer flap 21 that covers the rear end wall of the body is cut away on its lower edge to provide a locking tongue 32 that, when the same is folded over the inner flap 21', enters a slit 33 formed in the flap 21', whereby the two flaps are separably locked together over the rear end wall 13 of the body; it being noted that in the blank the inner edges of the flaps 21 and 21' are separated from the walls 13 and 14 by cuts *r*.

The free edges of the side wall flaps 19 are

equipped with tongues 34 that interlock, when the flaps are folded, with slots 35 in the bottom wall 12 of the body. Continuous with the narrow ends of the side walls 18 of the body are side wall wings 36 that are marked off from the side walls 18 by fold lines *s*, and, in the built up form of the box, are folded in between the front end wall 11 of the body and its flap 10; the free edge of the latter being supplied with tongues 37 that, when the flap 10 is folded down over the inner side of the front end wall 11, enter slots 38 in the bottom wall 12.

The manner in which the carton is set up and its parts interlocked has, to a considerable extent, been indicated above in connection with the description of the blank, but may be briefly outlined as follows.

The side walls 18 are bent to vertical position on the fold lines *h*, and the narrow front end wall 11 is bent to vertical position on the fold line *b*. The side wall wings 36 are folded inwardly on the fold lines *s* to lie against the inner side of the front end wall 11, and the end wall flap 10 is then folded downwardly over the wings 36 and its tongues 37 interlocked with the slots 38. When the side walls 18 have been folded upwardly, the side wall flaps 19 are then bent inwardly and downwardly to lie against the inner sides of the side walls 18 and locked in such position by the tongues 34 entering the slots 35. The side wall flanges 20 are then bent to horizontal position on the fold lines *k*.

The side walls 24 of the cover may then be bent upwardly on the fold lines *m* and their side wall flaps 25 then bent downwardly and inwardly and interlocked by means of the tongues 26 and slots 27, the wings 28 having previously been folded inwardly so as to lie between the side walls 24 and the side wall flaps 25. The side wall wings 29 are then bent inwardly, and the end wall 16 of the cover is then bent upwardly on the fold line *f* to overlie the wings 29, and the end wall flap 17 is then bent inwardly and downwardly over the inwardly folded wings 29 and locked in place by the tongues 30 engaged with the slots 31.

If desired, there may be cut out of the cover end wall 16 a display tab *T* separably held in the plane of the wall during manufacture of the blank by thin connecting strips 39 in the line of cut, which strips may be readily broken to permit the display section or tab *T* to be bent upwardly on its upper edge to the display position illustrated in Fig. 2.

The cover portion of the carton having thus been shaped up, the top wall 14 of the body is bent downwardly on the fold line *d* and the locking tongues 22 are inserted through the slots 23 of the side wall flanges 20, thereby securely locking said top wall 14 against edgewise displacement laterally. This produces the assembled box in the opened position shown in Fig. 2, wherein it will be seen that the cover member is hinged to the top wall of the body along the fold line *e*, which is preferably scored sufficiently to render it flexible.

Comparing Figs. 1 and 3 with Fig. 2, it will be seen that the hinged cover member, in the closed position of the box fits down over the open front portion of the box body completely covering the opening and with its end and side walls 80 overlapping the end and side walls of the front portion of the body, thereby fully protecting the contents of the box. In the open position, the cover member is thrown upwardly and backwardly to rest on the top wall 14 of the body, and 85 in such position it constitutes an upper tray in which the merchandise may be displayed. Both the inner and outer surfaces of both the body and the cover may carry printed advertising matter, which is displayed to advantage when the box 90 is in open position, and the tab *T* may carry the name or trade-mark of the goods or other indicia.

The inwardly folded flaps of the side and end walls of both the body and the cover have two 95 practical functions. In the first place, being locked in place they greatly strengthen and rigidify the said walls and, in the second place, they form smooth and rounded edges on the side and top walls of both body and cover which do not 100 easily become torn or frayed in handling, and give to the structure a neat and attractive appearance.

I claim as my invention:

1. A paper-board display carton comprising a 105 box body having a top wall extending over its rear portion and a cover hinged to the forward edge of the top wall and adapted to enclose the front portion of the box body or be positioned on said top wall for display purposes, said cover 110 having an end and side walls having flaps hinged to their free edges and folded inwardly and locked in parallel relation therewith, and said side walls having inwardly folded wings at their ends extending beneath the flaps of the end and 115 side walls respectively.

2. A paper board display carton comprising a box body having a top wall extending over its rear portion, and a cover hinged to the forward edge of the top wall, said cover having a two-ply 120 end wall and a display section cut out of one ply of said end wall at its base continuous with the bottom edge of the other ply whereby it may be swung upwardly to a display position when said cover is raised and folded back onto said 125 top wall.

3. A paper board carton having a bottom wall formed with slots in the forward portions of its side edges, side walls continuous with the side edges of said bottom wall, inwardly extending 130 flanges on the rear portions of the top edges of said side walls for supporting a top wall of the carton, and side wall flaps on the front portions of the top edges of said side walls, said flaps being folded down against the inner sides of 135 said side walls and having locking tongues on their free edges engaged with the slots of said bottom wall.

WILBUR C. WALLBANK.
